BOX OFFICE CONTROL SYSTEM

Ralph L. Thompson, New Hyde Park, N. Y.; Jacqueline E. Thompson, administratrix of said Ralph L. Thompson, deceased, assignor to Neptune Meter Company, New York, N. Y., a corporation of New Jersey

Application June 7, 1949, Serial No. 77,539

3 Claims. (Cl. 235—92)

1

The present invention relates in general to box office control systems, and more particularly to a box office control system for drive-in theatres.

With relatively few exceptions, the drive-in theatres built in this country operate according to standard box office technique as used at any local theatre. Each time an admission is paid in accordance with common practice, a ticket is issued to the purchaser to be later surrendered to the doorman, who retains half the ticket stub, returning the other half of the stub to the purchaser. In operating the drive-in theaters a modification of the standard procedure is normally employed in that a number of "runners" are used by each of the cashier's booths. These "runners" approach the car awaiting admission to the drive-in theatre, count the number of occupants and collect the required number of admissions. The "runner" then returns to his booth and turns over the money collected to the cashier, who in turn issues the required number of admission tickets. The "runner" then returns to the car and turns over the issued tickets to the driver thereof. The driver then proceeds with the car and its occupants to an entrance where a doorman collects the tickets, returning the stubs to the driver, the stubs retained being deposited in a suitable receptacle.

From the above outline of the box office control system as used in present day drive-in theatres, it will be appreciated that this system is both costly and cumbersome, leading to unwarranted delays in admitting the cars to the theatre proper, the possibility of collusion of the cashiers, runners, and doormen, with no adequate way of fixing responsibility, and the attendant trash problem presented by the returned ticket stubs.

It is therefore an object of my present invention to provide a box office control system for a drive-in theatre in which the "runners" and doormen are eliminated, and wherein the cashier completes the entire transaction of collecting the admissions and admitting the cars and occupants into the drive-in theatre proper.

Another object of the present invention is to provide a box office control system for drive-in theatres in which the cashier at the booth will register the admissions, the registry of the admissions forming a transaction count which is correlated with an actual car count made at the time of entry of the automobile into the theatre.

A further object of this invention is to provide a box office control system for drive-in theatres of the general character indicated in which the admissions, number of transactions, car counts,

etc., are registered on visual and/or printing counter wheels thereby eliminating the need for issuing the usual theatre tickets.

Still another object of this invention is to provide a control system of the general character indicated in which admissions of various types may be registered and recorded, as for example, adult admissions, children admissions, taxable passes, and free passes.

Still a further object of my invention is to provide a box office control system of the character indicated in which the number and type of admissions are indicated by an overhead signal and/or a remotely positioned signal to call general attention to the type of transaction completed by the cashier.

Yet another object of the invention is to provide a box office control system for drive-in theatres of the character described which will meet the requirements of the U. S. Internal Revenue Department for the collection of taxes on theatre tickets, which has heretofore been computed on the serial numbers printed on such tickets.

And another object of this invention is to provide a box office control system for drive-in theatres of the character described which shall consist of relatively few and simple parts, inexpensive to manufacture, which shall be positive and accurate in operation, which shall have a large variety of application and yet be practical and efficient to a high degree in use.

Other objects of the invention will in part be obvious and in part hereinafter pointed out.

The invention accordingly consists in features of construction, combinations of elements, and arrangements of parts which will be exemplified in the construction hereinafter described, and of which the scope of application will be indicated in the appended claims.

In the accompanying drawings forming a part of this specification in which one of the various possible illustrative embodiments of this invention is shown, and wherein similar reference characters designate corresponding parts throughout the several views,

Fig. 1 is a schematic view of the entire box office control system, including the register and printer, and the overhead indicator, while

Fig. 2 is a schematic wiring diagram of the control system, the necessary operating mechanisms being shown therewith.

The several objects of my invention are accomplished by providing in each collection booth of a drive-in theatre a register incorporating thereon a series of telephone dials, a dial being

provided for each type of admission to be collected. Operation of the telephone dial by the cashier when collecting the admissions will operate a relay circuit to advance a set of counter wheels a number equal to the admissions collected. The operation of the telephone dial will complete a circuit to advance a separate set of wheels to register transaction. Thus, each admittance into the drive-in theatre will provide a registration of the transaction and the admissions.

A treadle switch is also provided in the above outlined system whereby a car count is registered. Each car entering the theatre will pass over the treadle switch to complete a circuit for the advancement of still another set of counter wheels, the totals of the car-count counter and the transaction counter giving a positive check on the admissions made.

The system as more fully described herein-after, is characterized by a remote or overhead indicator which is operated in conjunction with the admission counter to provide a visual indication of the transaction completed.

Special provisions are incorporated in the box office control system to provide accurate counts of the special admissions collected, as for example, children admissions, taxable passes, and free passes. In collecting such admissions a transaction count is normally not necessary, particularly in the case of children who would be accompanied by at least one adult to drive the car.

Referring now in detail to Fig. 1 of the drawings, the numeral 10 designates a box office control system for a drive-in theatre comprising a register 11 for the collection booth under the jurisdiction of a cashier, a relay and junction box 12 connected thereto as by cable 13, a register and printer 14 connected to the box 12 as by a cable 15 and connected via said junction box and cable 16 to a treadle switch placed in the roadway or entrance to the theatre, and an overhead indicator 18 connected to the register 11 through the junction box 12 and a cable 19. The overhead indicator is of the usual type in which a sectionalized enclosure is provided with a cover glass divided into a corresponding number of panels, each of the panels being etched, masked or suitably marked with numeral designations, usually in serial order. As will hereinafter be described, a lamp in each of the sections, when energized, will illuminate the corresponding individual panel. It will be appreciated that the system as shown in the drawings and thus far described may easily incorporate the register 11, the junction box 12, and the register and printer 14 as a single unit if so desired; the separate units as shown are for the purpose of illustration.

The cashier register 11 is provided with a series of telephone dials 22, 23, and 24; a dial being provided for each type of admission to be collected. In the drawings, the dial 22 has been designated for adult admissions, the dial 23 for children admissions, and the dial 24 for taxable passes.

Referring now to Fig. 2 of the drawings, the dial 22 is shown connected into a relay circuit for operating the counter wheels and the overhead indicator 18. The telephone dial 22 is of the usual type having a rotatable face plate 28 provided with the ten finger openings 29 and the stop 30. Fixed to the back of the dial are three switches 31, 32, and 33; the switches 32 and 33 being tied together by an insulating bar 34. The

switch 32 is normally held open and the switch 33 held closed by an insulated pin 36 when the dial plate 28 is in its home position as shown in the drawings. The pin 36 is adapted to be rotated with the face plate to permit the switch 32 to close and the switch 33 to open. The switch 31 is normally closed when the dial is in its home position but is adapted to be opened upon rotation of the face plate 28 in dialing the number of admissions paid. The release of the face plate and its subsequent return to its home position will oscillate an insulated pin 37 against the arm of the switch 31 causing the switch to be opened and closed a number of times corresponding to the number dialed.

The telephone dial 22 is also provided with a fourth switch 40 which is normally open. Co-acting with the switch 40 is a pivoted lever arm 41 and an insulated pin 42. Rotatable with the face plate 28 of the dial is a spring biased cam 43 pivoted to said plate as at 44. The action of the cam is such that upon rotation of the plate 28 in dialing a number, the cam will abut the lever 41 rotating the same in a counterclockwise direction to momentarily close the switch 40. The return of the face plate 28 to its home position will not close the switch 40 a second time due to the rotation of the cam 43 about its pivot 44 upon engagement thereof with the lever 41; the spring 45 returning the cam to the position as shown within the arcuate portion of the lever 41.

One arm of the switch 32 is connected by a lead 48 to the low side of a suitable source of power supply, while the other arm of said switch is connected by a lead 50 through the primary winding 51 of a transformer 52 to the high side of the power supply 49. Thus the initial movement of the face plate 28 in dialing the number of admissions collected will permit the switch 32 to close to energize the transformer 52.

The secondary winding 53 of the transformer is connected at one end to an arm of the switch 31 by a lead 54. The other arm of the switch 31 is connected by a lead 55 through the energizing winding 56 of a stepping magnet 57 to the other side of the secondary winding 53. The stepping magnet 57 is provided with an armature 58, the movement of which each time the coils 56 are energized will actuate the pulsing arm 60 and the rotary switch arm 61 of a single level step switch 62. It will be apparent at this point that each time the number of admissions collected is dialed, the initial movement of the dial will permit the switch 32 to close to energize the transformer 52. The energization of the transformer will supply the voltage source for number pulsing switch 31 and the stepping magnet 57.

The stepping switch 62 is provided with a contact 64 adapted to be engaged by the pulsing arm 60, and a series of contacts 65 adapted to be engaged sequentially by the switch arm 61, the contacts 65 being here shown connected to individual lights 66 of the overhead indicator 18. The pulsing arm 60 is actuated to engage the contact 64 in harmony with the advance of the rotary switch arm 61 after the first impulse received by the coil 56 of the step switch. It will be noted that the first contact of the series of contacts 65 are not otherwise connected into any circuit. The reason for this is in the closed contact 31. The contact 31 will be opened and then closed a number of times only upon the return 75 of the face plate 28 to its home position. The

contact 32 however, will be closed immediately upon the initial movement of the dial. The transformer 52 will thus be energized and through the closed switch 31 energize the stepping magnet 57. The switch arm 61 will thus be advanced one step although no count has been initiated by the returning face plate 28. The first unconnected contact of the bank will thus prevent a false count from being registered.

The contact 64 of the stepping switch 62 is connected by a lead 70 through the energizing coil 71 of a stepping relay 72, and by lead 73 to the high side of the power supply 49. The armature of the relay 72 is adapted to advance a set of counter and/or printing wheels 74. Thus each time the switch 31 is opened and closed on the return of the face plate 28 to its initial position, the stepping magnet 57 is energized to actuate the switch arms 60 and 61. The step by step advance of the switch arm 61 will cause the switch arm 60 to engage the contact 64, each engagement completing an energizing circuit for the relay 72. The wheels 74 will thus be advanced to give the total admissions collected.

Means is now provided in the box office control system for registering the number of transactions made.

To this end a stepping relay 76 is provided, the energization of which will advance a set of counter and/or printing wheels 77. The energizing coil 78 of the relay 76 is connected at one end by a lead 79 to the supply line 50, and at the other end by a lead 80 to the lead 50 between the switch 32 and the transformer winding 51; the transformer 52 and the relay coil 78 being in parallel. Each time the switch 32 is closed by the initiating movement of the face plate 28, the relay 76 is energized to advance the counter 77 one number.

To correlate the number of transactions set up on the transaction counting wheels 77 with the actual number of cars permitted to enter the drive-in theatre, the treadle switch 17 is placed in the roadway leading into the theatre so that a car entering will close the switch to complete an energizing circuit for the coil 84 of the relay 85. Energization of the relay 85 will advance the car count wheels each time a car enters the theatre. The totals of the car count wheels and the transaction wheels can then be compared.

It will be noted that the circuit for energizing the relay 85 will cause an actuation of the wheels for each axle passing over the treadle. It will be understood that the wheels 86 may be advanced one whole number for every double energization of the relay 85, or a binary counting circuit can be interposed between the treadle and the relay 85 to provide a single energization thereof for each double actuation of the treadle switch.

Means is now provided to operate the overhead indicator 18 upon the completion of each transaction and to maintain the indicator in operation until the next transaction takes place so that a visual indication is had as to the last transaction completed.

To this end the light relay 87 is provided having a normally open switch 88 adapted to be closed upon energization of the relay coil 89. One end of the coil 89 is connected by a lead 90 to the power supply line 50, while the other end of the coil is connected by a lead 91 through the switch 33 and lead 92 to the other power lead 48. One side of the open switch is connected by a lead 93 to the lead 90, while the other side of the switch is connected by a lead 94 through the

lights 66 of the overhead indicator 18 to the contacts 65 of the stepping switch.

When the face plate of the dial 22 is rotated to initiate the admission count, the switch 33 of the dial is opened thereby opening the energizing circuit of the relay coil 89. With the relay deenergized, the associated switch 88 will be opened, thereby breaking the circuit of the overhead indicator. The switch 33 will remain open as the face plate is rotated in dialing the admission number and during the return thereof to its home position. The circuits previously described for advancing the stepping switches will function to advance the counter wheels 74 and to position the switch arm 61 in engagement with a contact 65 corresponding to the admissions collected. When the face plate of the dial 22 returns to its home position the admission pulsing circuit will be broken by the opening of the switch 32, and the indicator circuit will be completed by the closing of the switch 33. Relay 87 will be energized and the switch 88 will be closed. The overhead indicator circuit will then be completed through a contact 65 and the engaging switch arm 61. The circuit will remain completed until such time when a new transaction takes place. Meanwhile, for the purposes of checking, or otherwise, the overhead indicator remains operating.

Means is now provided to return the rotary switch arm 61 of the stepping switch to its home positions.

To this end the resetting magnet 96 is provided in the stepping switch, one end of the energizing coil 97 thereof being connected by a lead 98 to one side of the transformer secondary 53, while the other end of the coil is connected by a lead 99 through the normally open switch 40 to the other side of the secondary winding.

Initiation of a transaction will close the switch 40 momentarily to energize the reset relay 96 to home the switch arm 61. Since switch 32 is closed at the same time switch 40 is closed, the transformer 52 will be energized to supply the voltage source for the reset relay circuit. The opening of the switch 33 at the same time will open the overhead indicator circuit so that the return of the switch arm 61 to its initial position will not give a false or changing reading thereon.

The homing of the rotary switch arm 61 will not actuate the pulsing switch arm 60.

The box office control system thus far described will provide a count of the adult admissions, a count of the number of transactions, a car count, and an overhead indication of the admissions collected. As shown in Fig. 1 of the drawings, a second dial 23 is provided for registering the count of children admissions. Since the primary purpose of this system is for checking receipts of a drive-in theatre and the unlikelihood of children driving cars, the transaction relay and its counter wheels are not included in the counting and indicating circuits associated with the children admission dial 23. Otherwise the circuits as described for the dial 22 are used for counting and indicating the children admissions.

The dial 24 of the register is provided to record the number of admissions on passes on which a revenue tax must be collected. The dial 24 may operate the same type of circuits herein described to indicate and record the admissions. It is probable however that full admission adults and taxable pass moviegoers will occupy the same car. In such a case the operation of the dials 22 and 24 will cause the transaction relay to be energized

twice; whereas the car count total will only be advanced one count. For this reason I prefer to leave out the transaction relay 76 from the taxable passes circuits and substitute therefor the pass transaction pushbutton 100. In a situation where passes alone are offered for admission the pushbutton 100 is depressed to operate the counter wheels 101 of the register and printer. When a car of mixed admissions passes the toll both, the adult, children and passes can be registered in the normal manner, the pushbutton 100 being left alone since the transaction is being registered by the action of the switch 32 of the dial 22.

In the situation where free passes are presented, as for example by vending machine service men, no check on admissions is necessary. The pushbutton 100 will however have to be depressed to bring the totals of the transaction counters in agreement with the car count.

It will thus be seen that there is provided a box office control system for drive-in theatres in which the several objects of this invention are achieved and which is well adapted to meet the conditions of practical use.

Thus in the operation of the box office control system described, a car and its occupants will approach the check point represented by the toll booth at the entrance to the theatre and come to a halt. The cashier assigned to the booth will note the number of occupants and the types of admissions represented thereby. The admissions are then collected by the cashier and the car with its occupants is permitted to proceed into the theatre proper, in so doing, rolling over the treadle switch placed in the roadway.

The cashier will then dial the admissions collected on the appropriate dials 22, 23, and/or 24. Assuming that the last transaction registered comprised two adult and two children admissions, then the overhead indicator would present an indication as shown in Fig. 1 of the drawings. In dialing the new transaction, the initiation of the dialing operation by the cashier will prepare the counting circuits for a new pulsing cycle. The switches 32 and 40 will be closed, the switch 32 preparing the counting circuit for the pulsing cycle by energizing the transformer 52, and the switch 40 resetting the stepping switches. At the same time the switch 33 will be opened to deenergize the indicator relay 87 to extinguish the last transaction indicated thereon. Closing of the switch 32 will also actuate the transaction relay 76, so that a count is added to the wheels 77 for each pulsing cycle. Comparison of the car count wheels and the transaction wheels can readily be made.

It will be appreciated that the various counter wheels described in the within specification may include printing wheels and a periodic print may be made on a tape of the transaction totals, or

each transaction may readily be recorded on such a tape.

As various embodiments can be made of the above invention, and as various changes can be made in the embodiment set forth above, it will be understood that all matter herein set forth or shown in the accompanying drawings is to be interpreted as illustrative and not in a limiting sense.

10 Having thus described my invention, I desire to secure by Letters Patent:

1. A box office control system for drive-in theatres comprising a counting circuit including counter wheels, means for pulsing said counting circuit a number of times corresponding to the number of admissions collected from each car as it passes a check point to advance the counter wheels a number equal to the pulses of the pulsing cycle, a stepping switch advanced by the 15 pulses of said counting circuit, an indicator connected to said stepping switch, means for energizing said indicator upon completion of the pulsing cycle, said means operating to deenergize said indicator at the beginning of a subsequent 20 pulsing cycle, and means for resetting said stepping switch upon initiating said subsequent pulsing cycle.

2. A box office control system for drive-in theatres comprising a counting circuit, a telephone 30 dial, a switch actuated by the initial movement of the dial to energize the counting circuit, switch means actuated by the return of the dial to its initial position to provide a number of impulses in said energized circuit corresponding to the number 35 dialed, an electro-magnetic counter advanced a step for each impulse in said circuit, a stepping switch advanced a step for each impulse in said circuit, an indicator connected to said stepping switch for indicating the number of impulses, and a switch operated by said dial at the completion of the pulsing cycle to energize said indicator, said last switch deenergizing said indicator upon initiating a subsequent dialing operation.

3. A box office control system for drive-in theatres according to claim 2 including an electro-magnetic counter adapted to be advanced one step upon actuation of said first switch by said dial, and a fourth switch actuated by said dial 45 upon initiation of the dialing operation to reset said stepping switch.

RALPH L. THOMPSON.
